Primary Examiner — Cathron C Brooks*Assistant Examiner* — Andrew T Nemeth(74) *Attorney, Agent, or Firm* — Novick, Kim & Lee, PLLC; Allen Xue; Hyun Woo Shin(57) **CLAIM**

I claim the ornamental design for a display screen with animated graphical user interface, as shown and described.

DESCRIPTION

FIG. 1 is a front view of a first image in a sequence for a display screen with animated graphical user interface, showing my new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The broken lines shown in the figures, including the symbols, letters and numbers, are for the purpose of illustrating portions of the article, and form no part of the claimed design.

The appearance of the display screen with animated graphical user interface transitions sequentially between the images shown in FIGS. 1-6. The process or period in which one image transitions to another image forms no part of the claimed design.
